UNITED STATES PATENT OFFICE.

JOSHUA B. BARNES, OF SPRINGFIELD, ILLINOIS.

BLOW-OFF VALVE FOR STEAM-BOILERS.

No. 830,557.

Specification of Letters Patent.

Patented Sept. 11, 1906.

Application filed January 8, 1906. Serial No. 295,102.

To all whom it may concern:

Be it known that I, JOSHUA B. BARNES, a citizen of the United States, residing at Springfield, in the county of Sangamon and State of Illinois, have invented a new and useful Improvement in Blow-Off Valves for Steam-Boilers, of which the following is a specification.

My invention relates to a blow-off valve for a locomotive or other steam-boiler, and has for its object to obtain a valve that can be easily and instantly opened and closed when under pressure, positive in action, and adapted for use as a check or feed valve.

The invention consists in features of novelty, as hereinafter described and claimed, reference being had to the accompanying drawings, forming part of this specification, whereon—

Figure 1 is a vertical longitudinal section through my improved blow-off valve (seen partly in elevation) and box therefor on line 1 1 in Fig. 2, showing a preferable means of connecting the box to the shell (broken away) of a steam-boiler; Fig. 2, a top plan view of the valve-box; Fig. 3, a front elevation thereof as seen from the left in Fig. 1; Fig. 4, a horizontal section through the valve and box detached from the boiler on line 4 4 in Fig. 1; and Fig. 5, a side elevation, to reduced scale, of the valve-box, showing a modified connection thereof with the boiler-shell.

Like letters and numerals of reference denote like parts in all the figures.

a represents a conical disk valve having a central stem 1 on its under side and adapted to fit the seat 2, which may be either of separate construction and removably fixed in the valve-box *b*, as shown, or integral therewith, as preferred.

From the upper side of the valve *a* and radial to the center thereof, at a suitable distance apart, project upright wings or webs 3, which unite with the preferably circular wall of a cylindrical pocket 4, projecting upward from the central portion of the valve *a* and open at the top, the outer peripheral edges or surfaces of the wings 3, which are preferably flush with the edge of the valve *a*, being in circular alignment to each other, or in lieu of being flush with the edge of the valve *a* they may be set back therefrom on its upper side.

Through the top of the box *b* is a circular screw-threaded opening 5, through which the valve *a*, with its combined parts 1, 3, and 4, is inserted, the opening 5 being closed by a

correspondingly-threaded circular cover 6, having a cylindrical recess 7 in its under side adapted to fit around and in contact with the outer edges of the wings 3, which are free to slide vertically therein, and thereby form a guide to the valve *a*. Within the pocket 4 of the valve *a* is placed a coiled spring *c*, which bears at its lower end against the bottom of the pocket 4 or upper side of the valve *a* and at its upper end against the closed end of the recess 7 in the cover 6, the said closed end having, preferably, a depending seat 8, which enters and holds the spring *c* in place therat. The box *b* is formed on one side above the valve-seat 2 with an inlet branch 9, having, preferably, a flange 10 at its outer end, in the face of which, around the opening of the pipe 9, is formed a circular recess 11. Within the recess 11 is preferably fitted steam-tight the open end of a thimble or cap 12, which registers with the opening of the inlet branch 9 and is formed externally with a spherical-shaped head or bead 12', adapted to engage steam-tight in a correspondingly-shaped opening in the outer shell 13 of a steam-boiler, the straight tubular portion of the thimble 12 beyond the head 12' projecting with its closed end into the water-space (not shown) behind the shell 13. Through the cylindrical wall of the said tubular portion are holes or perforations 14, which are arranged at suitable intervals entirely around and along the thimble 12, as shown, and prevent the passage therethrough into the valve-box 3 of any sediment or solid matter from the water in the boiler, the valve-box *b* and thimble 12 being firmly secured to each other and to the shell 13 of the boiler by studs (or bolts) 15, which are tapped into the shell 13 and, passing through holes in the flange 10, are tightened thereto by the nuts 15', or the box *b* may be fixed to the shell 13 by the studs 15 without the thimble 12, the opening through the shell 13 in this case registering with the opening of the inlet branch 9, or the outer end of the inlet branch 9 may be threaded externally and screwed directly into a correspondingly-threaded hole through the shell 13. The box *b* is formed, preferably, opposite to the inlet branch 9 and below the valve-seat 2 with an outlet branch 16, to the outer externally-threaded end of which is coupled a pipe or hose, as required.

The stem 1 of the valve *a* is adapted to slide at its lower or free end portion through a hole or guide 17, formed through the bottom of

the box *b*, the free end of the stem 1 projecting beyond the guide 17 between two opposite side cheeks or brackets 18, which depend from the box *b* thereat. To the brackets 18 and between the same, at a short distance (determined by the lift of the valve *a*) from the center of the stem 1, at one side thereof, is fulcrumed by a pin 19 one end of an arm or lever 20 of the second kind, which is adapted at 10 the said distance from its fulcrum 19 to engage or bear against the projecting end of the stem 1, the outer free end of the lever 20 having a cord or chain 21 attached thereto within reach of the operator from any convenient 15 part of the locomotive cab or boiler-room, as the case may be. Provision is also preferably made for enabling the lever 20 to be removed from its fulcrum 19 at one side of the valve-stem 1 and similarly fulcrumed to the 20 brackets 18 at the same distance from the stem 1 at the opposite side thereof, whereby the direction of the lever 20 and cord 21 can be changed as desired.

In operation by pulling on the cord 21 the lever 20 is forced against the end of the valve-stem 1, and thereby, owing to the leverage thereat, easily and instantly lifts or opens the valve *a* from its seat 2 against the combined pressure in the boiler and the tension of the spring *c* above the valve *a* into the position indicated by dotted lines in Figs. 1 and 3, and in so doing the water and steam from the boiler passes through the inlet branch 9 into the valve-box *b* and through the opening of the valve *a* and outlet branch 16 to waste, the sudden impact thereof in passing through the inlet branch 9 against the guide-wings 3 of the valve *a* causing a partial rotation of the latter at each operation, and thereby preventing uneven wear of the valve-seat 2. On releasing the cord 21 and lever 20 the valve *a* is instantly closed by the combined pressure from the boiler and the spring *c*. If desired, the valve *a* may be used as a 45 check-valve or for filling the boiler with water, in which case the lever 20 may be removed and a hose from a water-supply coupled to the outlet branch 16 of the box *b*.

In Fig. 5 the flange 10 and studs 15, with 50 the spherical-shaped head 12' of the thimble 12, before described, are dispensed with and the thimble 22 screw-threaded directly into the open end of the inlet branch 9' of the box *b* and into the shell of the boiler, respectively.

What I claim as my invention, and desire to secure by Letters Patent, is—

1. In a valve of the class described, the combination of a box containing a seat for the valve and having a removable cover, a 60 stem on the under side of the valve slidable at its free end through the wall of the box, a pocket on the upper side of the valve, wings on the valve uniting with the wall of the said pocket and slidable through the open end of a

recess in the said cover for guiding the valve, 65 a spring within the pocket between the valve and the closed end of the recess, an inlet to the box above the said seat, and an outlet from the box below the said seat, the said inlet registering with an opening through the outer shell of, and in communication with the water-space of a steam-boiler, means for fixing the box to the said shell and means for opening and closing the valve, substantially as described. 75

2. In a valve of the class described, the combination of a box containing a seat for the valve and having a removable cover, a stem on the under side of the valve slidable at its free end through the wall of the box, a pocket on the upper side of the valve, wings on the valve uniting with the wall of the said pocket and slidable through the open end of a recess in the said cover for guiding the valve, 80 a spring within the pocket between the valve and the closed end of the recess, an inlet to the box above the said seat, and an outlet from the box below the said seat, the said inlet having a flange and registering with the open end of a thimble projecting steam-tight 85 through the outer shell of, and into the water-space of a steam-boiler, and having perforations through its cylindrical wall within the said space, means for fixing the box to the said thimble and shell and means for opening 90 and closing the valve, substantially as described.

3. In a valve of the class described, the combination of a box containing a seat for the valve and having a removable cover, a stem 100 on the under side of the valve slidable at its free end through the wall of the box, a pocket on the upper side of the valve, wings on the valve uniting with the walls of said pocket and slidable through the open end of a recess 105 in the said cover for guiding the valve, a spring within the pocket between the valve and the closed end of the recess, an inlet to the box above the said seat, and an outlet from the box below the said seat, the said inlet registering with an opening through the outer shell of, and in communication with the water-space of a steam-boiler, a bracket 110 projecting from the box adjacent to the said stem, a lever of the second kind fulcrumed 115 to the bracket at one side of the said stem and adapted to bear against the free end thereof, a cord attached to the free end of the lever and means for fixing the box to the said shell, substantially as described. 120

In testimony whereof I have signed my name to this specification in the presence of two subscribing witnesses.

JOSHUA B. BARNES.
